US00D957378S

(12) **United States Design Patent** (10) Patent No.: **US D957,378 S**
(45) Date of Patent: ** *Jul. 12, 2022

(54) **MOBILE PHONE**

- (71) Applicant: **Samsung Electronics Co., Ltd.**, Suwon-si (KR)
- (72) Inventors: **Jae-Hun Seo**, Suwon-si (KR); **Won-Kyu Sung**, Seongnam-si (KR)
- (73) Assignee: **SAMSUNG ELECTRONICS CO., LTD.**, Suwon-si (KR)
- (*) Notice: This patent is subject to a terminal disclaimer.

(**) Term: **15 Years**

(21) Appl. No.: **29/759,826**

(22) Filed: **Nov. 25, 2020**

Related U.S. Application Data

- (60) Continuation of application No. 29/717,564, filed on Dec. 18, 2019, now Pat. No. Des. 904,380, which is a division of application No. 29/678,961, filed on Jan. 31, 2019, now Pat. No. Des. 902,900.

CLAIM

The ornamental design for a mobile phone, as shown and described.

DESCRIPTION

FIG. 1 is a front perspective view of a mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The evenly-spaced dashed broken lines in the figures depict portions of the mobile phone that form no part of the claimed design.
